Application filed April 15, 1901. Serial No. 56,018. Term of patent 14 years.

To all whom it may concern:

Be it known that I, DAVID J. 10 This design relates to the ornamentation of cotton, silk, woolen, paper, celluloid, and other fabrics.

15 The leading feature of the design is the representation of wreaths of holly leaves and berries, connected by streamers with bells and stars in the alternate spaces between the sides of the streamers and the wreaths. The

wreaths A are composed of holly leaves and berries and are connected by the diagonally-arranged streamers B, also of holly leaves and berries, and in the alternate triangular spaces between the streamers and the wreaths appear stars C and bells D, the bells being hung on ribbons E, running out from the streamers B. 20 25

What I claim is—

In testimony whereof I have signed this specification in the presence of two attesting witnesses.
